2 Sheets-Sheet 2

UNITED STATES PATENT OFFICE.

ELISHA E. STRONG, OF PARIS, FRANCE, ASSIGNOR TO UNDERWOOD TYPEWRITER COMPANY, OF NEW YORK, N. Y., A CORPORATION OF DELAWARE.

TYPEWRITING MACHINE.

Application filed February 14, 1924, Serial No. 692,720, and in France August 6, 1923.

This invention relates to the line-feeding and carriage-returning devices of revolute platen typewriting machines.

It is usual to return the carriage by means of the same lever that effects the line-feeding of the platen. Owing to the limited range of movement of such lever, it has been the practice for certain purposes to provide a separate crank which is geared to revolve the platen through very many line-space intervals at a single stroke; this sweep of the platen being useful for introducing envelopes, bill-heads and other workpieces. Where such platen-sweep mechanism has been employed, it has been customary to return the carriage by means of a hand-hold or lug which is usually provided upon the carriage-frame for that purpose.

An object of the present invention is to provide means for simplifying the manipulation of machines of this class. To this end, the usual line-spacing and carriage-returning lever may be disregarded or eliminated, and a single platen-sweeping crank may be caused to perform the additional function of returning the carriage. Generally this crank extends normally toward the back of the machine, but when revolving or sweeping the platen around, it is pulled upwardly and forwardly, and at this time it is designed to constitute a convenient hand-hold for returning the carriage; so that the platen may be swept around and the carriage returned by a single manipulation of said crank or handle.

It is one of the advantages of the invention that the usual step-by-step letter-spacing devices may be omitted, including the platen-driving pawl; and said platen-sweeping crank may be adjusted to give the platen either a single, double, triple, or quadruple line-spacing movement at each manipulation, so that ordinary line-spacing movements may be secured by the one crank or handle, whenever desired.

The improved device may preferably be mounted on the left hand of the platen-carriage for convenience of operation, and may include a lever swingable transversely to the path of travel of the carriage, having a pawl carried thereon arranged to engage with gearing for rotating the platen, and a pivoted handle on the lever to co-operate with the pawl for improving the operation of the device.

Heretofore, when operating a platen-sweep mechanism which includes a lever, pawl and gears or their equivalents, it has been found if the lever is speedily operated and abruptly caused to stop at the end of the stroke, as is the common practice, the gears and platen have a tendency to overrun, due to momentum of the moving parts. One of the features of the present improvements is to eliminate this undesirable tendency by arranging a handle on the lever to swing against the back of the pawl and forcibly hold the pawl in engagement with its gear during the entire platen-turning operation. Thus the handle is caused to act as a back-stop or locking means, and prevents all possible slippage between the pawl and the gear and overrunning of the platen at the time that the lever is abruptly arrested at the end of the stroke.

The lever-handle may be provided with a finger-engaging piece having extensions thereon for taking the finger-thrust to sweep the platen and to give the platen-carriage return movement.

Other features and advantages will hereinafter appear.

In the accompanying drawings,

Figure 1 is a perspective view of a fragmentary portion of a frame and platen-carriage of a standard Underwood typewriting machine with the invention attached thereto.

Figure 2 is a view, in side elevation, of a platen-carriage with the invention mounted thereon, showing the operating lever in normal position and the handle thereof ineffective to control the pawl.

Figure 3 is a view similar to Figure 2, showing the operating lever at the end of the stroke, and the handle thereof effective to lock the pawl against the gear to prevent slippage therebetween.

Figure 4 is a plan view of that shown in Figure 3.

Figure 5 is a portion of a sectional view taken on the line 5—5 of Figure 4, showing the bearing supports for the rod, gear, lever and adjustable stop.

The invention may be made to form part of a typewriting, adding or similar machine having a revolute platen, and is illustrated as applied to a standard Underwood typewriting machine. Referring to the

drawings, a platen-carriage 10 is mounted to travel to and fro laterally on rails or tracks in the usual manner. Only the rear bar-rail 10^a is shown. Journaled in side frames 12 of carriage 10, only the one at the left being shown, is a platen 11 for carrying and advancing, in the well-known manner, work-pieces inserted in the machine for typing.

10 The invention, designated as 13, comprises a combined line-spacing mechanism of wide range or platen-sweep device and a platen-carriage-return means, and may preferably be mounted on the left-hand end of the 15 platen-carriage 10 on plate-cover 14 over the side frame 12 to replace the usual line-space mechanism. The device 13 may be provided with connecting and supporting means in the shape of a brace-bar or base 20 15 secured to lie flat on cover 14, and rigidly mounted on said bar 15 may be a semi-circular, toothed, sector-piece 16, as shown in Figures 1 and 4.

The device 13 may also have a supporting 25 rod 17 extending longitudinally over the platen 11, the left end thereof being journaled in the sector-piece 16 and the opposite end supported on the right end of platen-carriage 10 in any suitable well-known manner, not shown. On the left end of rod 17, a gear-wheel 18 may be rigidly mounted in any conventional fashion to mesh with a pinion 19 fast on axle 20 of the platen 11 for rotating the latter. To operate device 30 35 13, a finger lever or crank 21 may be provided, having a lower fork-shaped portion 22, the ends thereof straddling gear-wheel 18 and loosely pivoted on the hubs of wheel 18, as shown in Figures 4 and 5. The free 40 45 50 end of lever 21 may comprise a crank-handle 23, pivoted at 24 to the lower portion 22 for a limited rocking movement between arresting members 25 and 26 on the latter. The handle 23 may be yieldingly held in its rearmost rocking position by a retractile spring 27, which is fastened between the lower portion 22 and handle 23 as on anchor-stud 28 of portion 22 and on downwardly-projecting lip 29 on handle 23 below the pivot point 24.

A pawl 30 may be pivoted between the forked ends of lever portion 22 and urged into engagement with the teeth on the periphery of wheel 18 by a compression spring 31. The latter may be pocketed in pawl 30 against displacement from its operating position, and may have its protruding end bearing against the adjacent shoulder or heel 23^a on handle 23, as shown in Figures 2 and 3. The arrangement of parts just described allows spring 31 to assist spring 27 in its action.

An adjustable stop, comprising a bifurcated member 32 between the ends of which the toothed sector 16 sets, may be provided

to gage the throw of the lever 21 for determining the amount of platen sweep. The ends of member 32 are pivotally mounted one on the hub of gear 18 and the other on rod 17, as shown in Figure 5, for swinging about the latter as a center. The specific arrangement shown in Figure 5 of providing hubs on gear 18 allows for substantially supporting gear 18 on rod 17, and for providing relatively large and desirable pivoting surfaces on the outside of the hubs of gear 18 for the ends of portion 22 and bifurcated member 32.

The free end of stop 32 may have a finger-operated screw 34 threaded to project between the bifurcated portions of member 32, and means, such as clutch-block 35, on the leading end of screw 34 may be provided for engaging with the teeth on the sector-piece 16, whereby the stop 32 may be adjustably fixed in position.

Referring now to Figure 1, the device 13 may be adjusted by turning finger-screw 34 to control the engagement of clutch-block 35 with the teeth on sector-piece 16, and positioning stop 32 on sector-piece 16 to allow sufficient throw of lever 21 to give platen 11 the sweep required by the work-piece to be typed.

A pin 36, outwardly projecting from the side of stop 32 and extending into the path of movement of the crank 21, limits the backward movement thereof. The forward stroke of lever 21 may be limited by a fixed limiting-stop 37 secured on the forward right corner of the carriage-frame 12, and, on the upper side of said stop 37, a side stop 38 may project, as shown in Figures 1 and 2. The side stop 38 provides a substantial bearing to support the outer end of lever portion 22 during the platen-carriage-return motion. A spring 39 may serve to return the crank 21 to its normal rearward position against the pin 36 on stop 32. Said spring 39 may be coiled to surround rod 17 and may have one end thereof fastened to a guide-rod 40, carrying the usual downwardly-extending paper-fingers 41, and may have its other end extending outwardly from the coiled portion for anchoring on an inwardly-projecting stud 42 on lever portion 22.

The handle 23 is formed at its free end into a finger-engaging piece, which comprises an outward extension 43 and an upward extension 44, and is best shown in Figures 3 and 4. The device 13 is preferably operated by exerting finger pressure on extension piece 43 of the handle 23 to rock the latter on its pivot 24 against the action of springs 27 and 31 and cause the shoulder or heel 23^a to press against the adjacent part of pawl 30, forcing the latter into engagement with the teeth of gear 18, and thereafter to turn the lever 21 about rod 17 as an

axis until the lever 21 strikes limiting-stop 37. Meanwhile, the platen 11, through the gearing and the pawl-and-ratchet connection with lever 21, is swept through a distance corresponding to the adjustment of stop 32 on sector-piece 16. It should be noted that the pawl 30 is locked against disengagement from the gear 18 by shoulder 23^a while the handle 23 is operated.

10 This arrangement is a decided improvement over constructions used heretofore, because no matter how quickly the lever 21 is thrown and abruptly stopped, the engagement between the shoulder 23^a on handle 23 and pawl 30 provides positive locking or back-stop means against a tendency by the platen to overrun, due to the momentum of the moving parts.

After lever portion 22 strikes fixed limiting-stop 37, finger pressure may be exerted against extension piece 44 for giving the platen-carriage return movement. The limiting-stop 37, through side stop 38, offers desirable side support means to the lever 25 portion 22 during the carriage-return movement. On releasing of lever 21, spring 39 will automatically return the lever 21 to its rearward position against pin 36. A stud-handle 45 may be provided on the pawl 30 for swinging the latter out of engagement with gear 18 when it is necessary to turn the platen 11 backward, and a usual line-space wheel 46 mounted on platen-axle 20 with its usual co-operating roller-detent 47 35 may be provided, as shown in Figure 1, for positively holding platen 11 in position.

Operating the device 13 puts considerable stress on its fastening connections to the machine. Therefore, the brace-bar or base 40 15 may have its rear end bent downwardly and shaped to engage about a rear portion 48 of the side plate 12 of platen-carriage 10 to provide a brace or re-enforcement.

The device 13 may be adjusted to give the 45 platen line-space movement ranging from a single line-space to that corresponding to a complete revolution of the platen 11 or more for a single sweep of the crank 21, by properly proportioning the gears 18 and 19 and 50 making the distance between the teeth on gear 18 and sector-piece 16 correspond with a single line-space distance on platen 11.

Variations may be resorted to within the 55 scope of the invention, and portions of the improvements may be used without others.

Having thus described my invention, I claim:

1. In a typewriting machine, the combination with a revoluble platen, of platen-sweep mechanism therefor, including a pinion fixed to the platen, a gear-wheel meshing with the pinion, an actuating lever, a pawl carried by the actuating lever and spring-pressed into engagement with the teeth of 60 the gear-wheel, and an operating handle 65

swingably mounted on the lever adjacent the free end thereof, said handle including a heel directly engaging the pawl to hold the same pressed in engagement with the teeth when said handle is swung to move the lever 70 in platen-sweeping direction, thereby preventing slippage or over-running of the platen during the platen-sweeping operation.

2. In a typewriting machine, the combination of a revoluble platen, sweep mechanism for rotating the platen, including a ratchet-wheel and a driving pawl, an actuating lever for the pawl, a pivoted handle on said lever, a back stop forming part of 80 said handle, and yielding means normally holding the back stop ineffective, said stop during a platen-sweeping operation pressing against the pawl to hold the same in firm engagement with the ratchet-wheel. 85

3. In a typewriting machine having a revoluble platen, in combination with a platen-sweep mechanism including a pinion rotatable with the platen, a gear-wheel meshing with the pinion, a lever for operating said mechanism, a pawl-and-ratchet connection between the lever and the gear-wheel, a fixed stop mounted on the machine for limiting the throw of the lever in one direction, and an adjustable stop member for limiting the movement of the lever in the other direction, including means for locking said member in position, said lever having a rocking handle effective during the platen-sweeping operation to automatically 90 press the pawl in engagement with the ratchet, to eliminate slippage and on abrupt stoppage of the sweep motion of the platen to prevent overrunning thereof. 95

4. In a typewriting machine having a revoluble platen, in combination with a platen-sweep mechanism including a pinion rotatable with the platen, a gear-wheel meshing with the pinion, a rearwardly spring-pressed operating lever pivoted concentrically of 100 said gear-wheel, a pawl carried by the lever and forming a ratchet connection between said lever and the gear-wheel, a forward fixed stop, a rearwardly adjustable stop against which the lever normally rests, both 105 stops being arranged adjacent the path of the lever and co-operating therewith to limit the stroke thereof and consequently the rotation of the platen, and a handle 110 rockingly mounted on the lever having a shoulder adjacent the pawl, said handle automatically effective during the platen-sweeping operation to cause the shoulder to press directly against the pawl whereby to hold the same in engagement with the gear-wheel. 115

5. In a typewriting machine, the combination with a carriage, of platen-sweep mechanism including a base arranged to be fastened to the carriage, and an arm carried by the base for engaging the framework of 120 125 130

the carriage at the rear of the platen, beneath said base, whereby to brace the mechanism against stresses due to the platen-sweep operation.

5. 6. In a typewriting machine, the combination with a platen-carriage frame, of platen-sweep mechanism including a base for mounting the mechanism and for rigidly supporting the same on the carriage-frame, 13 said base having its rear end bent downward and shaped to engage around a portion of the carriage-frame to form a re-enforcing brace.

7. In a typewriting machine, the combination of a platen-carriage mounted for letter-space movement, a revoluble platen carried thereon, a device comprising a platen-sweep mechanism and platen-carriage-return means supported on the carriage, an operating lever for said mechanism, and a pivoted handle on said lever normally held ineffective by resilient means, said handle having extensions thereon for taking the finger-thrust to operate the sweep mechanism for 20 rotating the platen and for giving the carriage return movement, and effective during operation to lock the engaging parts of said mechanism against slippage and on abrupt stoppage of the sweeping operation to prevent overrunning of the platen.

8. In a typewriting machine, the combination of a platen-carriage mounted for letter-space movement, a revoluble platen carried thereon, a device including a platen-sweep mechanism and platen-carriage-return means supported on the carriage, an operating lever for said device, a pivoted handle on said lever, a back-stop forming part of said handle, and yielding means attached to the handle to normally hold the back-stop in an ineffective position, said stop during operation engaging parts of the mechanism to eliminate slippage and on abrupt stoppage of the sweeping operation to 40 prevent overrunning of the platen, and said handle having projecting extensions for taking the finger-thrust to operate the sweep mechanism for rotating the platen and for giving the carriage return movement.

9. In a typewriting machine, the combination of a platen-carriage mounted for letter-space movement, a revoluble platen carried thereon, and a device including 55 platen-sweep mechanism and platen-carriage-return means supported on the carriage, said mechanism comprising a pinion rotatable with the platen, a gear-wheel meshing with the pinion, a lever for operating the device, a pawl-and-ratchet connection between the lever and the gear-wheel, a fixed stop mounted on the carriage-frame for limiting the throw of the lever in one direction, and an adjustable stop member for limiting the movement of the lever

in the other direction including means for locking said member in position, said lever having a rocking handle effective during the platen-turning operation to continuously urge into engagement said connection 70 between the lever and the gear-wheel to eliminate slippage and on abrupt stoppage of the sweeping motion of the platen to prevent overrunning thereof, and said handle having projecting extensions for 75 taking the finger-thrust to operate the sweep mechanism for rotating the platen and to provide means whereby the carriage may be returned.

10. In a typewriting machine, in combination, a platen-carriage mounted for letter-space movement, a revoluble platen carried thereon, and a device including platen-sweep mechanism and a platen-carriage-return means supported on the carriage, said mechanism comprising a pinion rotatable with the platen, a gear-wheel meshing with the pinion, a rearwardly spring-pressed operating lever pivoted 85 concentrically of said gear-wheel, a pawl carried by the lever and forming a ratchet connection with said lever and gear-wheel, a forwardly fixed stop, a rearwardly adjustable stop against which the lever normally rests, both stops being arranged adjacent 90 the path of the lever and co-operating therewith to limit the stroke and rotation of the platen, and a handle rockingly mounted on the lever having a shoulder adjacent the pawl, said handle including projecting finger-pieces for taking the finger-thrust to operate the sweep mechanism for 100 rotating the platen and providing means whereby the carriage may be returned, said handle effective during a platen-sweeping operation to cause the shoulder to press the pawl and thereby act as a back-stop to eliminate slippage and on abrupt stoppage 105 of the sweeping operation of the platen to prevent overrunning thereof.

11. In a typewriting machine, in combination, a platen-carriage mounted for letter-space movement, a revoluble platen carried thereon, a device comprising platen-sweep mechanism and platen-carriage-return means supported on the carriage, an operating lever for said device, a stop for limiting the throw of the lever, and means on the stop to side support the free end of the lever during the carriage-return operation.

12. In a typewriting machine, in combination, a platen-carriage mounted for letter-space movement, a revoluble platen carried thereon, a device comprising platen-sweep mechanism and platen-carriage-return means supported on the carriage, a pivoted forwardly swinging lever to rotate the platen, a fixed stop mounted on the carriage for limiting the forward throw of 125 130

the lever, and an upwardly-projecting portion on said stop to side support the free end of the lever during the carriage-return movement.

5 13. In a typewriting machine, in combination, a platen-carriage mounted for letter space-movement, a revoluble platen carried thereon, and a device comprising platen-sweep mechanism and platen-carriage-return means supported on the carriage, said mechanism comprising a pinion rotatable with the platen, a gear-wheel meshing with the pinion, a rearwardly spring-pressed operating lever pivoted 10 concentrically of said gear-wheel, a pawl carried by the lever and forming a ratchet connection with said lever and gear-wheel, a forwardly fixed stop mounted on the carriage having an upwardly-projecting portion to side support the free end of the

lever during the platen-carriage-return movement, a rearwardly adjustable stop against which the lever normally rests, both stops being arranged adjacent the path of the lever and co-operating therewith to 25 limit the stroke and rotation of the platen, and a handle rockingly mounted on the lever having a shoulder adjacent the pawl, said handle provided with projecting finger-pieces for taking the finger-thrust to operate the sweep mechanism for rotating the platen and for giving the carriage return movement, and effective during platen-turning operation to cause the shoulder to press the pawl and thereby act as a back-stop to eliminate slippage and on abrupt stoppage of the sweeping operation of the platen to prevent overrunning thereof. 30 35
